UNITED STATES PATENT OFFICE.

WEBSTER L. MARBLE, OF GLADSTONE, MICHIGAN, ASSIGNOR OF ONE-HALF
TO FRANK H. VAN CLEVE, OF ESCANABA, MICHIGAN.

DESIGN FOR A COMPASS-CARD.

SPECIFICATION forming part of Design No. 34,336, dated April 9, 1901.

Application filed March 2, 1901. Serial No. 49,660. Term of patent 14 years.

To all whom it may concern:

Be it known that I, WEBSTER L. MARBLE, a citizen of the United States, residing at Gladstone, in the county of Delta and State of Michigan, have invented and produced a new and original Design for Compass-Cards; and I do hereby declare the following to be a full, clear, and exact description of the invention, such as will enable others skilled in the art to 10 which it appertains to make and use the same.

The accompanying drawing is a plan view of my newly-designed compass-card.

The leading or material feature of my design consists of a circular card having the points indicated thereon in the manner shown, the cardinal points being wide and conspicuous and the quarter-points narrow, all radiating from a central circular spot 1. The cardinal point 2 is diamond-shaped, with slightly-20 concave sides. The cardinal point 3 is triangular, with slightly-concave sides and deeply-concaved base, the angles being cut off when

they touch the central spot 1 and the circular periphery of the card. The two other cardinal points are alike, having narrow stems 4 radiating from the center spot 1 and broad lanceolate heads 4', whose points touch the periphery of the circle. The northeast, southeast, northwest, and southwest points are indicated by narrow bars 5, having parallel sides 25 and radiating from the center spot 1 toward the periphery of the circle. A diametrical line 6 is drawn from north to south and another, 7, from east to west.

What I claim is—

The design for a compass-card, substantially as herein shown and described.

In testimony whereof I affix my signature in presence of two witnesses.

WEBSTER L. MARBLE.
